(57) **CLAIM**

The ornamental design for an adhesive dispenser, as shown and described.

DESCRIPTION

FIG. 1 is a perspective view of an adhesive dispenser showing the new design;

FIG. 2 is a front elevational view, the opposite side being a mirror image thereof;

FIG. 3 is a side view, the opposite side being a mirror image thereof;

FIG. 4 is a top view thereof; and,

FIG. 5 is a bottom view thereof.

The broken line showing of a button on the adhesive dispenser is included for illustrative purposes only and forms no part of the claimed design.
